UNITED STATES PATENT OFFICE.

JOHN PEDERSEN, OF ST. LOUIS, MISSOURI.

GATE MECHANISM FOR FREIGHT-ELEVATOR HATCHWAYS.

Application filed October 28, 1926. Serial No. 144,742.

This invention relates generally to freight elevators, and has more particular reference to a gate mechanism for the elevator hatchways, the primary object of the invention residing in the provision of such a mechanism whereby the various gates are automatically released when the elevator reaches the various floors so that the gates may be moved downwardly flush with the elevator bottom wall and the floor of the building so that the entire floor elevation will be open to the elevator so as to permit bulky articles to be readily moved upon the elevator.

15 Heretofore, freight elevator gates have been so mounted that the same will rise vertically and stop at a position within the particular floor landing, making it impossible to load the elevator with articles of a height substantially equivalent to the height of the elevator.

A further object of the invention is to provide such a gate mechanism wherein the gates will be absolutely locked against movement until the elevator reaches a particular floor level, thus preventing access to the hatchway.

An additional object of the invention is to provide means whereby the various gates may be manually moved downwardly to open position and automatically secured in such open position when the elevator is at the respective floor landing of the particular gate.

35 A still further object of the invention is to provide means whereby the lowered gate will automatically move to raised position as soon as the elevator passes the particular floor landing and when once moved to elevated position will be automatically locked and prevented from movement in either direction.

Other objects will become apparent as the nature of the invention is better understood, the same comprising the novel form, combination, and arrangement of parts hereinafter more fully described, shown in the accompanying drawings and claimed.

In the drawings wherein like reference characters indicate corresponding parts throughout the several views:

Figure 1 is a fragmentary section through a freight elevator hatch way equipped with a gate mechanism constructed in accordance with the present invention, said figure dis-

closing one of the gates as entirely lowered, while the next adjacent gate thereunder is moved to slightly lowered position by reason of the first mentioned gate engaging the same during its lowering operation. 60

Figure 2 is a slightly enlarged detail vertical section taken substantially upon the line 2-2 of Figure 1 and looking in a direction toward the left as indicated by the arrows in said figure for more clearly disclosing the elevator control automatic gate locking and releasing mechanism.

Figure 3 is a greatly enlarged vertical section through two landings of the hatch way, one of the gates being lowered and automatically retained in such position by the presence of the elevator at the particular landing of said lowered gate.

Figure 4 is an enlarged fragmentary vertical section taken at right angles to the sectional views of Figures 2 and 3, and through one of the vertical guide rails at the side of the elevator hatch for more clearly disclosing the position of the gate within the guide at the upper end thereof 75 and the manner of attachment of the gate to the balancing weight cord, which weights automatically maintain the gates in raised position.

Figure 5 is an enlarged longitudinal section taken substantially upon the line 5-5 of Figure 4 for more clearly disclosing the anti-friction means between the corners of the various gates and the vertical guides at opposite sides of the hatch way, and 80

Figure 6 is a perspective of one of the weight cord attaching plates, one of which is provided at each upper corner of the various gates.

Now having particular reference to the drawings, A designates a freight elevator hatchway or shaft that extends vertically through the various floors of the building, the three disclosed in Figures 1 and 2 being designated by the reference characters a, b, 100 and c.

In carrying out my invention I provide at opposite sides of the hatchway directly at the various floor levels vertical channel bars 5-5 extending vertically through the center of each of which is a partition wall 6, see Figure 5. For each floor level there is provided a vertically slidable gate designated A', B' and C' respectively, the opposite vertical edges of which are slidably arranged 105 110

within said vertical channel bars 5—5 as clearly indicated in Figures 1, 4 and 5. For facilitating the easy vertical movement of the gates within said channel bars there is 5 arranged through each corner of the gates directly outwardly of the channel bars a cross pin 7 upon the opposite ends of which are arranged flanged rollers 8—8 the tread portions of which have engagement with the 10 edges of the channel bars at opposite sides thereof as is clearly illustrated in Figure 5. These rollers will also prevent lateral or transverse movement of the gates between the channel bars.

15 Arranged within openings 9 within the vertical partition walls 6 of the channel bars 5 at opposite sides of the hatchway are cord pulleys 10 which pulleys are arranged in vertically spaced relation with the floors of 20 the various floor levels a distance equivalent to substantially the height of the various gates A', B', and C' as clearly indicated in Figure 1. Trained over each pulley 10 is a length of cord or rope 11, the opposite ends 25 of which extend downwardly within the respective channel bar at opposite sides of the particular channel bar partition wall 6. Upon the upper corners of each gate are disposed generally T-shaped bracket plates 12, 30 the inner ends of the cross members of which extend within the channel bars and have attachment to the outer ends of the respective cords or cables 11 as in Figure 4. The opposite ends of these cords or cables are attached to weights 13 of square shape in cross 35 section and of such a cross sectional area as to prevent the turning of the weights within the channel bars in back of the channel bars respective partition plates 6. Obviously, the 40 pair of weights for each gate are heavier than the respective gates so as to normally maintain the gate in elevated position so as to close the hatch way to the particular floor level. The upward movement of the various 45 gates is prevented by reason of the fact that the inner ends of the cross members of the previously mentioned T-shaped brackets 12 will strike against the respective pulleys 10 as disclosed in the lower portion of Figure 1.

50 In further carrying out my invention certain mechanism is associated with either or both of the guide bars 5—5 for automatically maintaining the gate securely locked when in elevated position and for releasing the lock mechanism when the elevator reaches the various floor levels so that the particular gate may be lowered as indicated in Figure 3. However, it is only necessary that this mechanism be disclosed as associated with 55 one of the guide bars. This mechanism is more clearly illustrated in Figure 2, and as disclosed in this figure the mechanism is duplicated at each floor level. The units at each floor level consist of a short arm 14 pivoted to the hatch side of the channel bar

5 slightly above the floor of the particular landing and being of such a shape and so pivoted to the channel bar as to assume the inwardly projecting and slightly upwardly converging position as indicated in Figure 2, the extreme outer end of the arm being 70 equipped with a roller 15. The pivotal connection between the arm and the channel bar is such that the arm can not drop downwardly out of the position disclosed in Figure 2, but may be moved inwardly as disclosed by the position of the arm at the floor level a, at which floor level is the elevator B. Directly above this arm 14 is a pivotal arm 16 pivoted to the channel bar intermediate 75 its ends the lower end thereof normally projecting through an opening 17 in the adjacent wall of the channel bar and within that portion of the bar within which the counterbalancing weight 13 moves. The faces of the weight adjacent the outer wall of the channel bar are formed with vertical ratchet teeth 18 so as to be engaged by the inner ends of the respective arms 16 when the weights drop within the channel bar during the gate raising action for obviously locking the weights against reverse movement for consequently preventing the gate from being lowered.

80 The outer end of each arm 16 is equipped with a roller 19, while the outer end of each arm 16 is connected with the outer end of the next upper arm 14 by a cord or wire 20 for a purpose hereinafter more fully described.

85 The mechanism for each floor level further consists of a bell crank 21 pivoted to the channel bar 5 in vertical alignment with the arms 14 and 16 and being formed at its upper end with an inwardly extending finger 22 for projection through a slot 23 in the adjacent wall of the channel bar 5. Said fingers of the bell cranks are normally maintained out of the opening 23 by reason of a retractile coil spring 24 that interconnects the lower arm of each bell crank with the channel bar 5 so as to permit of the unhampered movement of the various weights 13 within the channel bar. The outer arm of 90 each bell crank is connected to the cord or wire 20 that interconnects the arm 16 of one floor level with the arm 14 of the next adjacent floor level.

95 A vertical ramp rail 25 is arranged on the elevator B in such a manner as to be adapted for engagement with the rollers of the arms 14 and 16 at each floor level, when the elevator B is brought to the particular floor level as illustrated in Figure 2.

100 As illustrated in Figure 1, the gate C' is in a closed position and when in such position the arms and bell crank will be in their normal positions, that is, the lower end of the arm 16 will have engagement with the ratchet teeth of the respective weight 13

for locking the gate against downward movement. As soon as the ramp rail 25 strikes the roller of the arm 16, this arm will be forced inwardly thereby releasing 5 the weight 13 so that the particular gate may be moved manually downwardly beneath the floor level to the position of the gate a' is shown in Figure 1. In order that the particular gate may be moved downwardly 10 so that the upper edge thereof will be flush with the floor of the landing, it is necessary that the next lower gate be released to a certain degree in order that it can be slightly moved downwardly by contact of the gate 15 being manually lowered. This provision is taken care of by reason of the ramp rail 25 engaging the roller of the arm 14 and moving the same slightly inwardly as indicated in Figure 2. This inward movement of the 20 arm 14 will cause the release of the arm 16 of the next lower floor level, thus releasing the weight 13 of that particular floor level gate. The upward pulling of the cord or wire 20 will so swing the bell crank 21 complementary to the next lower floor level as to cause the finger 22 to move into the channel bar 5 for limiting the upward movement 25 of the weight 13 so as to prevent the entire lowering of the gate b' to entirely open position. As soon as the elevator passes a particular floor level, the arms 14 and 16 will drop to their original positions.

For automatically maintaining each gate in lowered position, the inner side of each gate is provided adjacent its upper edge with a spring finger 26 over the upper end of which will automatically be projected a latch pin 27 slideable through a cross bar 28 in spaced relation with the hatch edge of 30 the floors of the various landings operable to locking position by reason of the lower end of the elevator B coming in contact therewith, see Figure 3. Each latch pin 27 is normally maintained in an inoperative 35 position by reason of a semi-elliptical spring 29 attached intermediate its ends to the outer end of the respective pin 27. As soon as the elevator B has passed beyond the particular floor level, the respective gate will be released 40 so that its weight will move the same to closed position.

In order that the space between the floor of the elevator and the floors of the different levels will be bridged when the elevator is 45 at the particular landing, the upper edge of each gate is equipped with a cross board 30, the ends of which terminate at the guide bars 5—5, see Figures 1 and 4.

The operation of the gate mechanism will 50 be readily apparent to those skilled in the art when considering the drawings in accompaniment with the foregoing specification and even though I have herein shown 55 and described the invention as consisting of certain detail structural elements it is

nevertheless to be understood that some changes may be made therein without effecting the spirit and scope of the appended claims.

Having thus described the invention, what 70 I claim as new and desire to secure by Letters Patent is:—

1. In a gate mechanism for freight elevator shafts, vertically slidable gate members for each floor landing of the shaft 75 which gate members are of a height greater than one half the height of the particular floors of the building, means for automatically elevating the gate to closed position, means for locking the gates in closed position, elevator operable means for releasing the gates whereby they may be lowered when the elevator reaches a particular floor landing, and means for partially releasing the next lower gate so that when the gate at the 80 floor adjacent the elevator is lowered, the same will contact the next lower gate and partially lower the same so as to permit of the full movement of the first mentioned 85 gate to open position. 90

2. In a gate mechanism for freight elevator shafts, vertically slidable gate members for each floor landing of the shaft which gate members are of a height greater than one half the height of the particular 95 floors of the building, means for automatically elevating the gate to closed position, means for locking the gates in closed position, elevator, operable means for releasing the gates whereby they may be lowered 100 when the elevator reaches a particular floor landing, and means for partially releasing the next lower gate so that when the gate at the floor adjacent the elevator is lowered, the same will contact the next lower gate 105 and partially lower the same so as to permit of the full movement of the first mentioned gate to open position, and means operable by the elevator at the particular landing for limiting the lowering of the next under 110 gate.

3. In a gate mechanism for freight elevator shafts, vertically slidable gate members for each floor landing of the shaft which gate members are of a height greater than 115 one half the height of the particular floors of the building, means for automatically elevating the gate to closed position, means for locking the gates in closed position, elevator operable means for releasing the gates whereby they may be lowered when the elevator reaches a particular floor landing, means for partially releasing the next lower 120 gate so that when the gate at the floor adjacent the elevator is lowered the same will contact the next lower gate and partially lower the same so as to permit of the full movement of the first mentioned gate to open 125 position, means operable by the elevator at the particular landing for limiting the low- 130

ering of the next under gate, said means being further operable to prevent the entire lowering of said next under gate.

4. In a gate mechanism for freight elevator hatchways, a vertically slideable gate for each floor landing of the hatchway, weight members so associated with each gate as to normally move the gate to elevated closed position, normally operable means for locking each gate to prevent the movement of the same in either direction, said means being releasable by the elevator when the

same reaches a particular floor landing so that the respective gate may be moved downwardly beneath the floor landing, automatically operable locking means for preventing the raising of the gate when the elevator is at the particular landing, said means being displaceable when the elevator passes the landing so that the gate will automatically move to elevated closed position. 15 20

In testimony whereof I affix my signature.

JOHN PEDERSEN.
